CLAIM

The ornamental design for a garbage receptacle, as shown and described.

DESCRIPTION

FIG. 1 is a diagrammatic perspective view of the garbage receptacle with the lid in the upright position.

FIG. 2 is a diagrammatic perspective view of the garbage receptacle with the lid in the reversed position.

FIG. 3 is a top plan view of the garbage receptacle with the lid in the upright position.

FIG. 4 is a bottom plan view thereof.

FIG. 5 is a front elevational view thereof, the rear elevational view being a mirror image of the front view.

FIG. 6 is a right side elevational view thereof; and,

FIG. 7 is a left side elevational view thereof.
